UNITED STATES PATENT OFFICE

2,615,488

BAG CLOSURE

Charles V. Brady and August F. Ottinger, St. Louis, Mo., assignors to Bemis Bro. Bag Company, St. Louis, Mo., a corporation of Missouri

Application June 30, 1950, Serial No. 171,524

1 Claim. (Cl. 150—1)

1

This invention relates to a bag closure, and more particularly, to the construction and fabrication of draw closure bags.

This application is a continuation-in-part of applicants' copending United States Patent No. 2,551,044, issued May 1, 1951 and entitled Bag Closure.

Briefly, the invention comprises, a bag closure having a ravel-resistant textile tape formed from a relatively wide moving web of textile fabric which is slit into a plurality of narrow strips, adhesive being applied only to the longitudinal raw edges of the strips. The adhesive is applied to the longitudinal edges of the fabric by applicators having wiping surfaces which in engaging the edges of the fabric are generally normal to the plane of the tape. Thus, application of adhesive is restricted primarily to the edges of the fabric as contrasted with the surfaces of the fabric.

The bag closure of this invention is of particular construction in that the adhesive on the tape is primarily at the two outermost longitudinal yarns. It is contemplated that there may be adhesive on some of the other longitudinal yarns immediately adjacent the two outermost yarns, but the amount of such adhesive progressively diminishes in the longitudinal yarns away from the outermost yarn. It is also contemplated that in one form of the invention, only the two outermost longitudinal yarns are adhesively secured to the transverse yarns of the fabric and the other longitudinal yarns are substantially free of adhesive.

The bag closure is relatively inexpensive as compared with tapes having woven selvages or with tapes having adhesive coatings over substantial portions of their areas. Other features will be in part apparent and in part pointed out hereinafter.

The invention accordingly comprises the elements and combinations of elements, features of construction and arrangements of parts which will be exemplified in the structures hereinafter described, and the scope of the application of which will be indicated in the following claim.

In the accompanying drawings, in which several of various possible embodiments of the invention are illustrated,

Fig. 1 is a perspective view of apparatus particularly adapted for producing the tape of this invention;

Fig. 2 is an enlarged section taken on line 2—2 of Fig. 1;

Fig. 3 is an enlarged sectional view of portions of tape and of the slitter illustrating certain features of the invention;

2

Fig. 4 is a section similar to that of Fig. 2 illustrating an alternative form of slitter;

Fig. 5 is a plan view of open-mesh material, showing the draw tape woven into the bag material; and,

Fig. 6 shows a segment of the web of Fig. 5 folded and seamed to form a bag.

Similar reference characters indicate corresponding parts throughout the several views of the drawings.

It has been found that tape-types of bag draw closures possess certain advantages over cord-types of draw closures. Among these advantages are the simplicity of manufacturing a bag having a tape-type of draw closure, particularly in anchoring the ends of the draw closure, and in appearance and ease of handling. Heretofore, tape for this purpose has been made on narrow looms with selvages woven along the longitudinal edges, or the tape has been made by applying adhesive over substantial areas to a wide web of textile material, drying the adhesive and then slitting the web so that adhesive is incorporated at the raw edges formed in the slitting.

Reference is hereto made to the aforesaid copending United States patent. Another approach to the problem is disclosed in Thomas M. Scruggs United States Patent 2,557,517, issued June 19, 1951. The principal objection to the use of textile tape over cords for draw closures

has been the expense, which necessarily is an important item in the low-cost high-production bag art. A substantial part of the increased expense of tape over that of cord is incurred in the attempt to prevent unraveling of textile tape at its raw edges. This invention has as a main feature the reduction in the cost of manufacturing a ravel-resistant tape to a substantially nominal figure.

Referring now to the drawing, there is shown in Fig. 1 apparatus for fabricating the tape. There is shown at 1 a supply roll of relatively wide textile sheet material. A relatively wide web 3 of textile fabric is unwound from the supply roll 1 and fed to slitter apparatus, generally designated 5. In passing through the slitter apparatus 5, the web 3 is longitudinally slit into a plurality of narrow strips 7, which are wound into a corresponding number of rolls 9 on a common axis.

Suitable pay-off and wind-up arbors 11 and 13 are shown for the rolls 1 and 9, respectively. It will be understood that at least the wind-up arbor is driven by suitable drive mechanism.

The slitter apparatus has a plurality of circular knives 15 on a transverse rotary shaft 17 and has a transverse rotary back roller or anvil

drum 19, which cooperates with the knives 15. Each knife 15 is generally in the form of a disc with a radially tapering periphery, thus providing a sharp V-shaped cutting edge 21. As shown, the knives are ganged on the shaft 17 so that the cutting edges 21 are axially spaced from one another or transversely spaced with respect to the longitudinal web and strips of textile material. For convenience of upkeep and repair, it is preferred that each knife 15 be a separate element 10 slidable onto the shaft 17, though the knives may be formed integral with one another. The anvil drum 19 is formed with a smooth cylindrical surface 23 adapted to engage or be closely adjacent the circular cutting edges of the knives 15. The knives and anvil drum are driven, in any conventional manner, with a peripheral speed substantially equal to the linear speed of the web 3.

Means is provided for applying liquid adhesive to the cutting edges 21 of the knives. This means may be a rotary pick-up roller 25 which rotates with the circular knives and is positioned to cooperate with the cutting edges thereof. A paste supply pot 27 containing liquid adhesive 29 is supported beneath the pick-up roller so that the latter dips into the adhesive and upon rotation transfers adhesive from the supply pot 27 to the cutting edges 21 of the knives. The pick-up roller has a peripheral surface which generally conforms with the periphery of the ganged knives, the roller 25 being formed with a plurality of annular V-shaped grooves 31 corresponding in number to the knives 15. The arrangement is such that the cutting edges of the knives are closely adjacent the apexes of the V-shaped grooves 31 in the pick-up roller. A doctor blade 33 is adjustably mounted on the supply pot 27 in a position so as to remove superfluous adhesive from the pick-up roller. This blade has a serrated edge 35 conforming with the peripheral surface of the pick-up roller. The doctor blade is adjusted so that only a light coating of adhesive is applied to the knives, as will be pointed out hereinafter.

The liquid adhesive used is one having fast-setting adhesive characteristics. Exemplary types of such adhesives are listed below:

Hot starch or dextrin mix
Polyvinyl alcohol solution
Polyvinyl acetate solution
Polyvinyl chloride solution
Cellulose nitrate solution
Cellulose acetate solution
Cellulose butyrate solution.

Additionally, the liquid adhesive should be thin or of light solid content so that it immediately strikes into the yarn and sets substantially instantaneously upon application to the fabric.

The textile fabric from which the tape is formed will depend upon the service to which the tape is put. Draw tapes for small, medium and large drawn closure bags may be formed from textile fabric as follows:

Small bags, 4.00 (yards/pounds) cotton sheeting
Medium bags, Osnaburg fabric
Large bags, 10½ oz. burlap.

Operation is as follows: The supply roll 1 of textile sheet material is on the pay-off arbor 11. The web 3 is unwound and threaded through the slitter, strips 7 being thereby formed which are wound up on the wind-up arbor 13. Suitable driving mechanism (not shown) causes rotation 70 of the wind-up arbor, knives 15, the anvil drum 75

19 and the pick-up roller 25. The rotating pick-up roller transfers a limited amount of liquid adhesive 29 to the rotating knives 15, which then apply the adhesive to the strips 7 as they are slit from the web 3. Liquid adhesive is thus applied to the raw edges formed in slitting the web into narrow strips.

As mentioned previously, only a limited quantity of adhesive is applied to the textile material by the slitting knives. Ideally, the quantity and location of adhesive 29 is such that of the longitudinal yarns 37 of the tape, only the two outermost 39 are adhesively secured to the transverse yarns 41 at their ends 43. In this connection it will be observed that the sharp knife edges 21 inherently tend to restrict application of adhesive 29 to only these outermost longitudinal yarns 39 or conversely to only the two yarns immediately adjacent to and on opposite sides of any one knife edge during slitting (Fig. 3). Each knife may be considered as an adhesive applicator having wiping surfaces 45 which engage the moving strips 7 on opposite sides thereof at their longitudinal raw edges and which are generally transverse to the planes of the strips 7.

There is some tendency for the liquid adhesive to spread to the other longitudinal yarns adjacent the outermost yarns 39, but this is restricted by limiting the quantity of adhesive on the knives by adjustment of the doctor blade and by employing a liquid adhesive of low solid content which strikes right into the yarn. These two factors will vary with the weight and weave of the textile fabric, but may be readily determined. In any event, outermost yarns 39 carry the greatest quantity of adhesive applied to the fabric and the quantity of adhesive on other longitudinal yarns adjacent the yarns 39 will progressively diminish away from the edges of the fabric.

The resultant tape wherein the two outermost longitudinal yarns 39 of the fabric carry most of the adhesive is advantageous for the purposes herein in that the expense of adhesive is held to a nominal figure and in that drying or setting problems are also minimized. Slitters commonly run at high speeds, thus necessitating fast drying in order to prevent the rolls 9 from being adhered together and to prevent the various layers built up in the rolls 9 from being adhered together. Moreover, the finished tape is superior to more heavily coated textile tapes in that it is flexible and easy to handle.

An alternative embodiment of the apparatus is shown in Fig. 4. The apparatus is similar to that of Figs. 1-3 except for the shape and action of the slitters. A shear type of slitter is employed here as contrasted with the pinch or cleave type shown heretofore. The construction of such a shear type of slitter is detailed in the copending United States patent application of Thomas M. Scruggs et al. Serial No. 55,804, entitled Slitting and Winding Apparatus and filed October 21, 1948.

As shown, a plurality of knives 47 are ganged upon a rotary shaft 49. Each knife comprises a central hub 51 and an annular knife-edged flange 53 extending outward at one end of the hub and raked back toward the other end of the hub so as to be of hollow conical form. Cooperating with the knives is a rotary anvil 55 comprising a plurality of annular member 57, each having a hub 59 and a flange 61 extending outwardly at one end of the hub and raked toward the other end of the hub. The knives 47 and the anvil members 57 are assembled on their respective shafts 49 and

63 so as to rake toward one another with the circular edges 65 on the knives overlapping the cylindric rims 67 on the anvil members and providing shears.

Both the knives and anvil are rotated to slit a textile web passed therebetween. Otherwise, the construction and operation are as described heretofore in connection with the Figs. 1-3 embodiment. Liquid adhesive is applied to the cutting edges 65 of the knives by means of a pick-up roller 69 and the knives transfer the adhesive to the longitudinal edges of the strips which are slit from the web of textile material. Application of adhesive is controlled so that the two outermost longitudinal yarns of the strips receive most of the adhesive.

Referring now to Fig. 5, there is shown a continuous web 71 of woven material from which the bag of this invention is manufactured. The material may be of close-weave or open-weave nature. At the time that the web 71 is woven, the tape 7 is woven in near its upper selvage 73. This weaving is preferably such that it passes over and under pluralities of open-mesh threads such as shown at 75 and 77. This gives the tape 25 a certain looseness of weave that is desirable.

The bag web of Fig. 5 is then cut into segments substantially twice the desired bag width. Each segment is then folded centrally so as to bring the side and bottom margins together and they are seamed as by stitching 79 at the bottom and stitching 81 at the side, the latter being opposite the central fold. This stitching forms an anchor at 83 for the end portions of the tape which were formed by segmenting the bag web. The bag thus formed may then be turned if desired. It will be understood that after the bag is filled, the bag mouth is closed by grasping the tape adjacent the folded side and withdrawing it, at the same time pushing in the bag mouth.

As is apparent, the flat ends of the interwoven tape are firmly secured by the side-seam stitching. The light adhesive coating at the edges of the tape prevents unravelling during initial handling, especially while the tape is being woven in the bag material. It is at this time that unravelling should especially be prevented. Once the tape is woven into the bag, unravelling is no longer a serious problem because the bag material itself tends to prevent excessively harmful

unravelling of the tape. Moreover, even if unravelling of the tape should occur during closing and opening of the bag mouth, the longitudinal strength and tension of the tape is not adversely affected and the longitudinal yarns of the tape are retained in place by the bag fabric.

In view of the above, it will be seen that the several objects of the invention are achieved and other advantageous results obtained.

As many changes could be made in the above constructions without departing from the scope of the invention, it is intended that all matter contained in the above description or shown in the accompanying drawing shall be interpreted as illustrative and not in a limiting sense.

We claim:

A bag composed of woven material and having a draw-type closure comprising a length of raw-edged flat fabric tape woven with the material of the bag, said length of tape encompassing the bag girthwise adjacent its mouth and being arranged flatwise with respect to the bag body, stitching securing together the ends of the tape, the tape being of such width as readily to be secured by the stitching, and the tape being coated with adhesive only at its longitudinal raw edges, the greater portion of said adhesive being immediately adjacent the two outermost longitudinal yarns at the opposite edges of the tape and the other longitudinal yarns being substantially free of adhesive, the adhesive thereby being merely sufficient to prevent unravelling of the tape during initial handling and while the tape is woven into the bag.

CHARLES V. BRADY.
AUGUST F. OTTINGER.
